CASSETTE TAPE PLAYER

Richard K. Althans, Long Grove, and Melvin H. Boldt,
Glenview, Ill., assignors to Zenith Radio Corporation,
Chicago, Ill., a corporation of Delaware

Filed Aug. 27, 1969, Ser. No. 18,865

Term of patent 14 years

Int. Cl. D14—01

U.S. Cl. D26—14

FIG. 1

FIG. 2

FIG. 3

Des. 217,155

PAGE 2

FIG. 4

FIG. 5

FIG. 6

FIG. 1 is a top plan view of a cassette tape player, showing our new design;

FIG. 2 is a right side elevational view thereof;

FIG. 3 is a front elevational view thereof;

FIG. 4 is a rear elevational view thereof;

FIG. 5 is a bottom plan view thereof; and

FIG. 6 is a perspective view thereof showing the top, left side, and front of the cassette tape player.

We claim:

The ornamental design for a cassette tape player, substantially as shown.
